UNITED STATES PATENT OFFICE.

CHARLES C. STEEL, OF WILLIAMSPORT, PENNSYLVANIA.

METALLIC RAILWAY TIE.

Application filed February 12, 1923. Serial No. 618,620.

To all whom it may concern:

Be it known that I, CHARLES C. STEEL, a citizen of the United States, residing at Williamsport, in the county of Lycoming and State of Pennsylvania, have invented certain new and useful Improvements in Metallic Railway Ties; and I do declare the following to be a full, clear, and exact description of the invention, such as will enable others skilled in the art to which it appertains, to make and use the same.

This invention relates to railway ties which are adapted especially for use in connection with mine railways.

The invention has been designed in order to provide a simply constructed, strong, durable, light-weight tie of this character made entirely of metal.

The improved tie consists of a comparatively narrow and shallow-channeled body member, the cross section of which is such that it may be entirely rolled to shape, separate rail engaging and gauge fixing lugs, and separate wedge engaging abutments formed from rolled metal bars.

The novelty in the invention resides in certain details of construction and the combination and arrangement of parts, which are hereinafter fully described and claimed, and illustrated in the accompanying drawing.

In the accompanying drawing which forms a part of this specification:—

Figure 1 is a perspective view of one end portion of a tie constructed in accordance with the present invention, showing a rail secured in place thereon;

Fig. 2 is a view similar to Fig. 1, except that the rail and wedge for holding the latter tight are omitted;

Fig. 3 is a longitudinal sectional view of one end portion of the tie, showing a rail secured thereon;

Fig. 4 is a transverse sectional view of a tie taken substantially on the plane indicated by the line 4—4 of Fig. 3; and

Fig. 5 is a side elevation, on a greatly reduced scale, of a complete tie constructed in accordance with the present invention.

Referring more particularly to the drawing in which similar reference characters are used to designate corresponding parts throughout the several views, the numeral 1 designates the body portion of the improved tie. This is straight from end to end and has its longitudinal edges turned or bent

downwardly to provide parallel supporting and strengthening ribs 2, the latter forming upon the lower or under-side of the body member 1 a longitudinally extending channel 3.

The channeled body member 1 is made of metal, preferably of high carbon steel, and is preferably rolled into shape. The longitudinal ribs 2 are inclined outwardly from their upper edge portions to their lower edges, and their lower edge portions are thickened in such a manner as to form beads 4. The beads 4, which are thicker than the normal thickness of the ribs 2, are formed by the thickening of the lower edge portions of the ribs from the outer sides only of the same.

Disposed upon the upper side of the body member 1 and located adjacent to but spaced slightly inwardly from the ends of the same, are rail engaging lugs 5, which also serve as gauge fixing lugs. These lugs 5 have base portions 6 which rest flat upon the upper side of the body member 1, and they also have upwardly but slightly inclined rail base-flange engaging portions 7 adapted to engage the inner base flanges of rails.

Disposed beyond the end of the body member 1 and extending above the same, that is, extending to a point located above the plane of the upper side of the base member, are hook-like wedge engaging abutments 8. These abutments 8 constitute the curved end portions of substantially J-shaped members 9 having straight portions 10, which constitute the bases for the hook-like abutments 8.

The straight portions 10 of the substantially J-shaped members 9 are disposed beneath the body member 1 in the end portions of the channel 3. The edges of the portions 10 engage the inner sides of the ribs 2, so that the members 9 cannot shift transversely in the channel 3.

The substantially J-shaped members 9 are bent from straight metal bars, which are rolled specially at their edges so that they conform to the shape of the lower or under-side of the channeled body member 1.

The rail engaging and gauge fixing lugs 5 and the substantially J-shaped members 9, constituting separate pieces of material from the body member 1, are rigidly secured to the latter by suitable securing elements. Preferably a single rivet 11 is passed through each of the lugs 5, the body member

1, and each of the members 9. The lowermost heads 12 of these rivets 11 are disposed in the channel 3 and are preferably flattened.

5 Ties constructed as described in the foregoing and as illustrated in the drawing may be used in connection with various kinds of railways, but since they may be made with comparatively narrow and shallow channeled 10 body members they find special application in connection with mine railways, where light weight ties are desirable and where ties provided with a quick and easy-to-operate rail engaging means are desirable. 15 In using the improved tie it is the intention to place it directly upon a mine floor and to arrange the rails R of the mine railway track upon the end portions of the body member 1 of the tie so that the inner base- 20 flanges of the rails will be engaged by the upwardly inclined portions 7 of the lugs 5. After this has been done wooden wedges 13 may be driven between the web portions of 25 the rails and the hook-like abutments 8 to securely clamp the rails to the end portions of the tie and at the proper distance apart.

From the foregoing description, taken in connection with the accompanying drawing, the construction, use and advantages of 30 the invention will be readily understood.

It is obvious that various changes in form, proportion, and in various details of construction may be made without departing from the spirit and principle of the invention or sacrificing any of the advantages 35 thereof, and hence it is to be understood that such may be done within the meaning and scope of the appended claims.

What is claimed is:—

40 1. In a metallic railway tie, a straight body member provided on its lower side with a longitudinally extending channel, a separate rail engaging lug disposed upon the upper side of said body member and located adjacent but spaced slightly inwardly from one end of the latter to engage the inner base flange of a rail, a separate J-shaped member having its straight portion disposed in the end portion of said channel 45 and its curved portion extending beyond the end of said body member and above the latter, means for securing said lug and

said J-shaped member to said body member, the curved portion of said J-shaped member being spaced from said lug, and a wedge to 55 fit against the inside of the curved portion of said J-shaped member to hold a rail in engagement with said lug.

2. A metallic railway tie comprising a straight body member having its lower side 60 provided with a longitudinally extending channel, separate rail engaging lugs disposed upon the upper side of said body member and located adjacent but spaced slightly inwardly from the ends of the latter 65 for engagement with the inner base-flanges of rails, separate substantially J-shaped members having straight portions disposed in the end portions of said channel and curved portions extending beyond the ends 70 of said body member and above the latter in spaced relation to said lugs to form wedge engaging abutments, and a single securing element passing through each of said lugs, 75 said body member and each of said substantially J-shaped members and rigidly securing these parts together.

3. A metallic railway tie comprising a straight body member having its longitudinal edges downturned to form longitudinal 80 supporting and strengthening ribs and a channel on the lower side thereof, separate rail engaging lugs disposed upon the upper side of said body member and located adjacent but spaced slightly inwardly from the ends of the latter for engagement with the inner base-flanges of rails, separate hook-like wedge engaging abutments extending above said body member and spaced outwardly from said lugs and having straight 85 base portions disposed beneath said body member in said channel, the longitudinal edges of the base portions of said abutments engaging the inner sides of said ribs whereby to prevent transverse shifting of said 95 abutments in said channel, and a single securing element passing through each of said lugs, said body member and the base portion of each of said abutments and rigidly securing these parts together. 100

In testimony whereof I have hereunto affixed my signature.

CHARLES C. STEEL.
